UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND-BRAKE FOR RAILWAY-CARS.

1,356,084.

Application filed September 30, 1918, Serial No. 256,173. Renewed August 30, 1920. Serial No. 407,062.

To all whom it may concern:

Be it known that I, JOHN F. O'CONNOR, a citizen of the United States, residing at Chicago, in the county of Cook and State 5 of Illinois, have invented a certain new and useful Improvement in Hand-Brakes for Railway-Cars, of which the following is a full, clear, concise, and exact description, reference being had to the accompanying 10 drawings, forming a part of this specification.

This invention relates to improvements in hand brakes for railway cars.

The object of the invention is to provide 15 an exceedingly simple and relatively inexpensive geared hand brake for railway cars wherein is employed a vertical staff.

In the drawing forming a part of this specification, Figure 1 is an end view of a 20 portion of a gondola car showing my improvements applied thereto, part of the car being broken away. Fig. 2 is an enlarged, vertical, sectional view taken substantially on the line 2—2 of Fig. 3 and illustrates the 25 arrangement of the winding spool and gearing. Fig. 3 is a horizontal, sectional view taken substantially on the line 3—3 of Fig. 2.

In said drawing, 10 denotes the end wall 30 of a gondola car, 11 a platform for the brakeman, 12 an upper bearing bracket for the vertical brake staff 13, and 14 a depending lower bearing bracket secured preferably to the underside of the bottom of the 35 car body. The staff 13 is provided, at its upper end, with the usual form of hand wheel 15, and, adjacent the platform 11, is provided with a ratchet wheel 16 and a foot-controlled pawl 17.

40 At its lower end, the staff 13 has mounted thereon a chain-winding spool 18. The spool 18 is formed with a preferably integral gear 19 at its lower end, the entire spool and gear being freely rotatable on the 45 staff 13. The staff 13, at its extreme lowest end, is formed with a portion 20 of reduced size rotatably mounted in the bearing bracket 14, and intermediate the reduced section 20 and the main portion of the 50 staff, the staff is provided with a squared section, as indicated at 21. Mounted on the squared section 21 of the staff is another smaller gear 22, which will, of course, be rotatable in unison with the staff. At one 55 side of the staff is provided a stud shaft

23 preferably in the form of a headed pin, the same being supported in suitable bearings in the bracket 14 and a plate 24 riveted to the bracket, as indicated in Figs. 1 and 2. Rotatably mounted on the stud shaft 60 23 are two gears of different diameters, 25 and 26, preferably formed integrally but in any event adapted to rotate in unison. The gear 26 is made larger than the gear 25 and the gear 26 meshes with the gear 22, 65 whereas the gear 25 meshes with the gear 19 of the spool 18. Suitable cotters 27—27 are passed through the lower ends of the staff and the stud shaft to prevent accidental disengagement. 70

As clearly indicated in Fig. 1, the spool 18 and associated gears are disposed below the level of the bottom of the car so that the brake chain (one link of which is indicated at 28) will readily wind about the 75 spool when the staff is rotated. By employing the arrangement disclosed, it is evident that I obtain an increased leverage ratio, since rotation of the staff 13 will be communicated from the gear 22 to the gear 26 80 and thence through the gear 25 to the spool 18. In this way, I am enabled to obtain a much more effective braking tension with the usual staff and hand wheel than heretofore, and, at the same time, the number of 85 parts is reduced to a minimum. The arrangement is exceedingly compact and inexpensive, and all the parts are disposed in such manner as to avoid danger to the operator and clear from injury which might 90 result from the striking of the parts by any stationary projection while the car is moving.

Although I have herein shown and described what I now consider the preferred 95 manner of carrying out my invention, the same is merely illustrative, and I contemplate all changes and modifications that come within the scope of the claims hereof.

I claim:

1. In a device of the character described, the combination with a car body having a depending bearing bracket secured thereto at the bottom and an additional bearing bracket, of a vertical brake staff rotatably 105 mounted in said bearing brackets, a chain-winding spool rotatably mounted on said staff near the bottom thereof, a gear rotatable in unison with said spool, a gear carried by, and rotatable in unison with, said 110

staff, a stud shaft carried by said depending bracket and two gears of different diameters mounted on said stud shaft, said two gears being rotatable in unison, one of said two gears meshing with the first mentioned gear and the other of said two gears meshing with said gear rotatable in unison with the staff.

2. In a device of the character described, 10 the combination with a car body having bearings thereon for a vertical brake staff and including a bracket at the bottom of the car body, of a vertical brake staff rotatably mounted in said bearings, a spool rotatably

mounted on said staff below the bottom of 15 the car, a gear rotatable in unison with said spool and located at the bottom thereof, a second gear rotatable in unison with the staff and disposed below the spool gear, and lever ratio multiplying gearing interposed 20 between said gear rotatable in unison with the staff and the gear rotatable in unison with the spool.

In witness that I claim the foregoing I have hereunto subscribed my name this 25 24th day of Sept., 1918.

JOHN F. O'CONNOR.
